(57) CLAIM

The ornamental design for a hair clip, as shown.

DESCRIPTION

FIG. 1 is a perspective view of a hair clip showing my new design thereof;

FIG. 2 is a front elevational view thereof;

FIG. 3 is a rear elevational view thereof;

FIG. 4 is a left side elevational view thereof;

FIG. 5 is a right side elevational view thereof, wherein the broken lines are for environmental purposes only and form no part of the claimed design;

FIG. 6 is a top plan view thereof;

FIG. 7 is a bottom plan view thereof, wherein the broken lines are for environmental purposes only and form no part of the claimed design; and,

FIG. 8 is a perspective view thereof, illustrating an opening configuration of the hair clip.
